UNITED STATES PATENT OFFICE.

JOSE SAMPERE, DECEASED, LATE OF NEW YORK, N. Y., BY MARIE SAMPERE PAUSAS, ADMINISTRATRIX, OF NEW YORK, N. Y., ASSIGNOR, BY MESNE ASSIGNMENTS, TO A. C. CHENEY PIANO ACTION CO., OF CASTLETON, NEW YORK.

SHEET-ADJUSTING APPARATUS.

1,208,840.

Specification of Letters Patent. Patented Dec. 19, 1916.

Original application filed March 2, 1911, Serial No. 611,896. Divided and this application filed December 18, 1912. Serial No. 737,509.

To all whom it may concern:

Be it known that I, MARIE SAMPERE PAUSAS, a citizen of the United States, and a resident of and whose post-office address is 5 the city, county, and State of New York, am the administratrix of JOSE SAMPERE, deceased, late a citizen of the United States, inventor of certain new and useful Improvements in Sheet-Adjusting Apparatus, of 10 which the following is a specification, reference being had therein to the accompanying drawings.

My invention relates to improvements in sheet adjusting apparatus and has particular reference to and is illustrated in the accompanying drawings in its application to a piano player.

This application is a division of my previous application. Serial No. 611,896.

20 Referring to the accompanying drawings Figure 1 is a front elevation partly in section of an apparatus illustrating an application of my invention, and Fig. 2 is a plan view looking down upon the same with 25 parts omitted.

5 is the outer framework in which the usual spools 6 and 7 are suitably mounted and upon which the tracker bar 8 is secured. One of these spools may be driven in any 30 suitable manner as by a chain 9 engaging the sprocket 10, secured to the shaft 11, provided with pinion 11' engaging the gear 50 of the spool.

13 is a bracket in which the other end of 35 the other shaft 60 may be mounted and from which it is forced rightwardly by the coil spring 14, said bearing being retained within the bracket 13 by any suitable means such as the collar 15 held by the pin 16. At the 40 opposite extremity of the shaft 60 is mounted the arm 17. One end of this arm or bracket is suitably secured to the shaft 19 which is preferably bent at right angles at the opposite extremity serving as a bearing 45 20 for the cam 21 mounted within the bracket 22 secured to the frame 5. This cam is secured to the lever 23 by the pin 24 so that as the lever 23 is moved, the cam 21 is moved within the bracket 22 thereby causing 50 the shaft 19 to shift the spools 6 right-

wardly or leftwardly. The lever 23 is pivoted to the lever 25 which is pivoted to the pneumatic provided with chambers 26—27 connected by the bar 28.

29 and 30 are tubes communicating respectively with each of the chambers 26 and 27 of said pneumatic and the valve mechanism which controls the action of the same.

The action of my device is as follows: When the sheet of music such as 31 in passing from one roll to the other shifts laterally it actuates a valve which controls the flow of air through the tubes 29 and 30 thus causing the pneumatic to actuate, and through its connecting mechanism to shift 65 the spool 6 in the opposite direction to the direction in which the sheet 31 shifts. Thus the cam 21 is rotated by the levers 23 and 25 when the pneumatic inflates or deflates and this shifts the bar 19 rightwardly or 70 leftwardly and likewise the bearing 60 to which the bar 19 is connected by the arm 17, thus shifting the spool 6. This is provided for by the coil spring 14 which projects the bar or bearing 60 rightwardly against the 75 collar 15, always under slight tension.

Of course it will be understood that various modifications may be made without departing from the spirit of the invention as claimed.

I claim:

In a device of the class described, a pneumatic, a spool bearing, a spool and sheet thereupon, a cam operatively connected between the bar and said pneumatic, a tracker 85 over which said sheet passes, and connections between said bearing and said pneumatic and parallel with said spool which are adapted to shift parallel with said spool and adjust said bearing when said pneumatic is 90 operated, said spool provided with resilient means to oppose longitudinal movement and said connection provided at one end with means adapted to be operated upon by said cam actuated by said pneumatic.

MARIE SAMPERE PAUSAS,
Administratrix of Jose Sampere, deceased.
